UNITED STATES PATENT OFFICE.

CHARLES F. GAUNT, OF BIRMINGHAM, ENGLAND.

BUTTON.

Application filed March 10, 1921. Serial No. 451,364.

To all whom it may concern:

Be it known that I, CHARLES FREDERICK GAUNT, of the city of Birmingham, England, a subject of the King of Great Britain, 5 have invented certain new and useful Improvements in Buttons; and I do hereby declare that the following is a full, clear, and exact description thereof.

This invention has reference to the manufacture of those uniform buttons and other like buttons in which the body of the button is formed of compressed leather or horn or other pierceable non-metallic body part furnished with a metallic shank. Heretofore 10 various means have been adopted for fixing the metallic shank to the compressed leather or horn or other non-metallic body part, one method being to employ a U shaped wire shank the ends of which are spread slightly 15 apart and are forced through holes in a metal back plate and are spread farther apart in the compressed leather or horn or other body part. It is found in practice however that sometimes these wire shanks 20 pull out as their ends have not sufficient hold in the compressed leather or horn or other non-metallic body part of the button. This defect it is the object of my invention to 25 overcome.

It has also previously been proposed for a 30 button to be furnished with a cage like shank formed with three, four or more arms secured to the back of the button by the outwardly turned ends of the arms, engaging 35 with a ring or back plate fixed to the button, and said ring or back plate has been fixed to the back of the button by being spread in a previously formed under cut or other recess in the back of the button.

According to my invention I employ a 40 loop shaped button shank which has a multiplicity of prongs preferably four, although I do not confine myself to any particular number, said prongs forming the rays of a 45 star shaped metal blank, said prongs being bent from the center so as to each form approximately the letter U and thus together form a hollow cage like shank, and the ends of the prongs are preferably pointed and 50 turned apart slightly and may be plain, jagged or barbed and these prongs are driven into the compressed leather, horn, or other pierceable non-metallic body part of the button so that the end portions of the shanks 55 are embedded in said body part and spread apart and form a good hold in the substance

of the button body so that they are prevented from pulling out under the strains to which the buttons are subjected when sewn on the garment.

A metallic back plate with inwardly or outwardly turned rim adapted to be forced into and be embedded in the substance of the button and pierced for the prongs of the shank to pass through may be used with said 60 multi-pronged shank and if desired the latter and said back plate may be fixed together before the rim of the back plate is forced into and thereby fixed to the leather or other pierceable non-metallic body part.

For full comprehension however of my invention reference must be had to the accompanying drawings in which similar reference characters indicate the same parts and wherein:

Figure 1 is a sectional elevation of a a leather or other non-metallic button made according to this invention. This view is taken on line X-X of Fig. 2 which is an inverted plan of said button;

Figure 3 is a plan of the star shaped blank for forming the multi-pronged shank of said button;

Figure 4 is a plan of a modified form of said blank;

Figure 5 is a sectional elevation of a modified form of said button;

Figure 6 is a sectional elevation of a further modification of the same, and

Figure 7 is a sectional elevation and plan 90 of a further modification of my invention.

A is the compressed leather or other non-metallic body of the button and B is the multi-pronged shank of the same which in the example illustrated is made from a four 95 rayed star shaped blank, Fig. 3, the prongs or rays 1 of which are bent from the centre 2 so that each opposite pair forms approximately the letter U and thus together form the hollow cage like shank. The outer ends 100 3 of the prongs 1 are preferably pointed so as the better to penetrate the leather or other non-metallic body A and their ends are spread apart slightly so that they will still further spread when forced into the leather 105 or other non-metallic body A.

In order to increase the frictional hold or grip of the prongs 1 in the compressed leather or horn or other non-metallic body part A of the button the end portions of the 110 prongs which engage in the said body part may be barbed, or jagged or roughened, see

Fig. 4, said barbs or the like projecting backwardly so as not to retard the forcing of the prongs of the shank into the body of the button, but to afford a considerably increased hold in the substance of the button, head against any pressure tending to draw the shank out from the main portion of the button. The prongs 1 of the cage like button shank may for additional security pass through corresponding holes pierced in a metallic back plate 5, which may be made with an outwardly turned flange 6 (Fig. 5) or an inwardly turned flange 7 (Fig. 6) which flange when pressed into the substance of the button further spreads outwardly or inwardly and thus obtains a firm grip in the substance of the body A of the button and affords extra security to the multi-pronged shank.

Or as a further modification (see Fig. 7) the said cage like button shank B may be secured to the metallic back plate 5 by passing through a corresponding number of holes pierced therein and then spreading outwardly the ends of the prongs on the inner side of the back plate 5 before the latter is secured to the button by being pressed therein and its flange spread outwardly or inwardly in the substance of the button as above described.

What I claim is as follows:

1. A button of a material which will permit of a prong being driven thereinto comprising a body and a shank secured thereto, said shank consisting of a unitary device having two pairs of prongs bent to U form, one pair being disposed at right angles to the other pair, said prongs being constructed and arranged to anchor in the body when driven thereinto.
2. A button of a material which will per-

mit of a prong being driven thereinto comprising a body and a shank secured thereto, said shank consisting of a unitary device having a plurality of pairs of prongs bent to U form, the extreme end of the prong of each pair being tapered and bent laterally away from the other prong of the pair whereby the ends of the prongs are caused to spread apart when driven into the body.

3. In a button the combination with the body thereof of a material which will permit of a prong being driven thereinto, a back plate having a plurality of openings and a circumferential flange adapted to be anchored in the body when driven thereinto, and a shank extending through the openings in the back plate and secured to the body, said shank consisting of a unitary device having two pairs of prongs bent to U form, one pair being disposed at right angles to the other pair, said prongs being constructed and arranged to anchor in the body when driven thereinto.

4. In a button the combination with the body thereof of a material which will permit of a prong being driven thereinto, a back plate having a plurality of openings and a circumferential flange adapted to be anchored in the body when driven thereinto, and a multi-pronged metallic cage-like shank the prongs of which are constructed and arranged to be driven into the body through said openings and to become anchored therein as they are driven.

In testimony whereof I have signed my name to this specification in the presence of two witnesses.

CHARLES F. GAUNT.
